UNITED STATES PATENT OFFICE.

EDWARD A. MACK, OF HUNTINGTON, WEST VIRGINIA.

GUY-WIRE TENSION EQUALIZER.

Application filed December 10, 1927. Serial No. 239,237.

This invention relates to equalizers and more particularly to equalizers to be employed with guy-wires.

An object of this invention is to provide an equalizer that shall be simple in structure, inexpensive to manufacture and more readily installed than devices heretofore employed for this work.

Another object of this invention is to provide an equalizer that shall over-come the difficulty usually encountered when it is desired to pull two or more guys to the same tension, which are attached to the same anchor rod.

These and other objects are attained by means of the device hereinafter described and illustrated in the accompanying drawings, wherein,

Figure 1, is a view in elevation of an installation employing two equalizers embodying the invention, and

Figs. 2 and 3 are enlarged views of an equalizer embodying the invention, taken 90° one to the other.

This invention comprises a clevis 11 of substantially V shape adapted to engage an eye 12 of an anchor rod 13 and an equalizer plate 14 provided with a plurality of spaced openings 15 for receiving the free ends of the clevis 11 and guy-bolts 16.

The plate 14 is preferably made from angle iron for the obvious purpose of giving it additional strength.

The openings 15 in the plate 14, that are adapted to cooperate with the guy-bolts 16, are preferably reamed out to cooperate with the concaved surface of a washer 17. The guy-bolts are provided with a threaded means 18 for tightening or loosening the

guys.

Figure 1 illustrates an installation, employing two of the present equalizers, one of which is being used with two guys, as shown at 21, and the other with three guys, as shown at 22.

One important advantage of the present equalizer is the time saved in performing numerous complicated guying jobs and in obtaining the proper tension in each guy-strand.

Other important advantages of the present equalizer are; its simple structure, inexpensiveness to manufacture and the expedient manner in which adjustment may be made in case the anchors have crept after completion of a job. It can be seen from the above, that

a line patrolman equipped with a wrench, can quickly adjust or take up the tension in each guy-strand in a very short time as compared to the time required to adjust such devices as have been heretofore employed for the purpose.

The guying of the structures in building wood pole lines amount to a considerable portion of the construction expense, especially on long span work, and the present equalizer, which is a simple inexpensive device, that has been found by experience to save both time and money, is considered to be a very advanced step in this particular art.

While I have illustrated and described this invention in connection with a two and three wire construction, it will be obvious to those skilled in the art, that other changes, modifications, substitutions, additions and omissions may be made in the equalizer without departing from the spirit and scope of the appended claims.

What I claim as new and desire to secure Letters Patent on, is:

1. An equalizer comprising a clevis adapted to engage an anchor rod, a plate having spaced openings therein for receiving the free ends of the clevis and openings adjacent to the first said openings, for receiving guy-bolts and means for adjusting the said bolts.

2. An equalizer comprising a V shaped clevis adapted to engage an anchor rod, a plate having spaced openings therein for receiving the free ends of the clevis and openings adjacent to the first said openings for receiving the free ends of guy bolts connected to wires and means for adjusting the tension of the wires with respect to the said plate.

3. In a guy wire equalizer for anchoring a plurality of guy wires to a single anchor, means associated with said equalizer for independently adjusting the tension of each guy wire.

4. A guy-wire equalizer comprising an anchor rod, a clevis adapted to engage the anchor rod, a plate having spaced openings therein for receiving the free ends of the clevis, means for fixing the clevis to the said plate, openings in the plate adjacent each of the first said openings for receiving guy-bolts connected to guy-wires, the last said openings having their outer surfaces formed for engaging and cooperating with the convexed side of a washer disposed on the said guy-bolt and threaded means for adjusting

the guy-bolts with respect to the said plates.

5. A guy-wire equalizer for anchoring a plurality of guy-wires to a single anchor comprising a substantially V shaped clevis adapted to engage an anchor rod, a plate having a pair of spaced openings for receiving the free ends of the clevis and openings adjacent the first said openings for receiving

guy-bolts connected to guy-wires and a separate means for adjusting the tension of each 10 guy-wire.

In testimony whereof, I have hereunto subscribed my name this 5th day of December, 1927.

EDWARD A. MACK.
